UNITED STATES PATENT OFFICE

MICHAEL SOCHA, OF CHICOPEE FALLS, MASSACHUSETTS

PROTECTIVE DEVICE FOR BANK CASHIERS' OR TELLERS' WINDOWS

Application filed July 3, 1930. Serial No. 465,662.

This invention relates to protective devices and has special reference to a cashier's or teller's window protector.

One important object of the invention is to improve the general construction of devices of this character.

A second important object of the invention is to provide an improved operating mechanism for devices of this character.

A third important object of the invention is to provide, in such apparatus, an improved arrangement having folding side wings to protect the person behind the window from lateral attack.

A fourth important object of the invention is to provide improved means for operating these wings.

With the above and other objects in view, the invention consists in general of certain novel details of construction and combinations of parts hereinafter more fully described, illustrated in the accompanying drawings and specifically claimed.

In the drawings:

Figure 1 is a rear or inside elevation of such a window, showing the device in connection therewith in its housed position;

Figure 2 is a section on the line 2--2 of Figure 1;

Figure 3 is a view similar to Figure 1 but with the protecting device raised;

Figure 4 is a section on the line 4--4 of Figure 3;

Figure 5 is a section on the line 5--5 of Figure 3;

Figure 6 is an enlarged detail elevation partly in section and showing the spring means used to raise the shield to operative position.

In the embodiment of the invention as here shown, it has been illustrated as being applied to a bank counter 10 having a screen 11 at its front which is provided with a window opening 12 covered in part by the usual grill 13.

Extending from the shield 14 to the floor 15 is a pair of tubes 16 located at opposite sides of the window and open at their upper ends. The confronting sides of these tubes are provided with longitudinally extending slots 17 and in each tube is a head or plunger

18 between which and the floor 15 is a coiled compression spring 19 urging the plunger upwardly. These plungers are connected by the lower edge of a guard screen 20 made of bullet proof material and working in a slot 21 formed in the shelf 14. The lateral edges of this guard screen work in the slots 17 and hinged to these lateral edges are side guards 22 which are normally folded against the rear face of the guard 20 but which are urged to open position by springs 23. The rear edge of each slot 17 is curved to form a cam 24 and then extends vertically to form a stop 25. Secured to the lower edge of the screen 20 and depending therefrom is a ratchet bar 26 having on its rear face upwardly facing ratchet teeth which are engaged by a dog 27 sliding through guides 28 and normally held in engagement with the teeth by a spring 29. A bell crank treadle 30 has one arm connected to the rear end of this dog 27 and its other end extending rearwardly and upwardly convenient to the foot of the person behind the window.

Also, the bar 26 is provided with rack teeth 31 on one side and these teeth are engaged by a gear 32 mounted on a rearwardly extending shaft 33 carrying an operating crank 34. The plungers or heads 18 are carried on stems 35 which project down through suitable openings in the bottoms of the cylinders 16 so that these heads are properly guided in their movements.

The shaft 33 is supported in swinging bearings 36 so that in using the gear 32 to actuate the latch bar, the gear may be swung into engagement with the rack teeth but, after the screen has been lowered, the gear may be swung out of such engagement so as not to interfere with rapid upward movement of the screen. When out of engagement the shaft 33 is supported by a keeper 37.

In operation, the screen is normally lowered as shown in Figs. 1 and 2 and the dog 27 is engaged with the ratchet bar to hold the screen in this position against the action of the springs 19. In the event of an attack the person behind the counter steps on the treadle and releases the dog so that the springs quickly raise the screen. As the

screen nears its upper position, the cam surfaces 24 permit the wings to fold outwardly until they engage the stop surfaces 25 against which they are held. Thus the employee is protected both in front and at his sides. 5 When it is desired to again house the device, the crank is rotated which draws the screen downwardly and, as it thus moves, the cam surfaces 24 act to fold the wings inwardly. 10 Thus when the screen is down and the dog engaged, it will be held ready for use another time.

There has thus been provided a simple and efficient device of the kind described and for the purpose specified.

15 It is obvious that changes may be made in the form and construction of the invention without departing from the principles thereof. It is not, therefore, desired to confine the invention to the exact form herein shown and described, but it is desired to include all such as come within the scope claimed.

I claim:—

1. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, tubes surrounding said springs and slotted to receive the hinged edges of the screen and wings, the slots in the tubes forming cams at their upper ends to control the movement of the wings in unfolding and folding, and springs connecting said screen and wings and urging the wings open.

2. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, tubes surrounding said springs and slotted to receive the hinged edges of the screen and wings, the slots in the tubes forming cams at their upper ends to control the movement of the wings in unfolding and folding, springs connecting said screen and wings and urging the wings open, and stops at the upper ends of said tubes limiting the opening of said wings.

3. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, means to open the wings upon upward movement of the screen and to close

the wings upon downward movement of the screen, a combined ratchet and rack bar depending from the screen and wherewith said dog engages, a gear engaging the rack bar, and crank means for operating the gear to lower the screen.

4. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, tubes surrounding said springs and slotted to receive the hinged edges of the screen and wings, the slots in the tubes forming cams at their upper ends to control the movement of the wings in unfolding and folding, springs connecting said screen and wings and urging the wings open, a combined ratchet and rack bar depending from the screen and wherewith said dog engages, a gear engaging the rack bar, and crank means for operating the gear to lower the screen.

5. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, tubes surrounding said springs and slotted to receive the hinged edges of the screen and wings, the slots in the tubes forming cams at their upper ends to control the movement of the wings in unfolding and folding, springs connecting said screen and wings and urging the wings open, stops at the upper ends of said tubes limiting the opening of said wings, a combined ratchet and rack bar depending from the screen and wherewith said dog engages, a gear engaging the rack bar, and crank means for operating the gear to lower the screen.

6. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, means to open the wings upon upward movement of the screen and to close the wings upon downward movement of the screen, a combined ratchet and rack bar depending from the screen and wherewith said dog engages, a gear engaging the rack bar, crank means for operating the gear to lower the screen, swinging bearings supporting the gear for movement into and out of engagement with the rack bar, and releasable means to hold said gear out of said engagement.

7. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, tubes surrounding said springs and slotted to receive the hinged edges of the screen and wings, the slots in the tubes forming cams at their upper ends to control the movement of the wings in unfolding and folding, springs connecting said screen and wings and urging the wings open, a combined ratchet and rack bar depending from the screen and wherewith said dog engages, a gear engaging the rack bar, crank means for operating the gear to lower the screen, swinging bearings supporting the gear for movement into and out of engagement with the rack bar, and releasable means to hold said gear out of said engagement.

8. The combination with a window opening; of a guard screen therefor normally held below said window opening, wings hinged to the lateral edges of the screen and normally folded thereagainst, springs urging said screen upwardly to a position behind the window opening, a releasable dog holding said screen downwardly against the action of the springs, tubes surrounding said springs and slotted to receive the hinged edges of the screen and wings, the slots in the tubes forming cams at their upper ends to control the movement of the wings in unfolding and folding, springs connecting said screen and wings and urging the wings open, stops at the upper ends of said tubes limiting the opening of said wings, a combined ratchet and rack bar depending from the screen and wherewith said dog engages, a gear engaging the rack bar, crank means for operating the gear to lower the screen, swinging bearings supporting the gear for movement into and out of engagement with the rack bar, and releasable means to hold said gear out of said engagement.

In testimony whereof I affix my signature.

MICHAEL SOCHA.
